UNITED STATES PATENT OFFICE.

RICHARD BRAMBACH, OF NORDHAUSEN, GERMANY.

DRIVING DEVICE FOR HOUSEHOLD-MACHINES.

No. 845,050.

Specification of Letters Patent.

Patented Feb. 26, 1907.

Application filed June 1, 1906. Serial No. 319,740.

To all whom it may concern:

Be it known that I, RICHARD BRAMBACH, a subject of the King of Prussia, and a resident at Nordhausen - am - Harz, Germany, have 5 invented a new and useful Improved Driving Device for Household-Machines, of which the following is a specification.

My invention relates to a driving device for machines, and has for its object a device 10 adapted to have machines to be driven by it readily connected to the same, and particularly adapted for use in private houses and the like.

More particularly, my invention relates to 15 a driving device for domestic or household machines, and in order that the details of construction and action of my invention may be more clearly understood reference is made to the accompanying drawings, in which—

20 Figure 1 is an elevation on the line B B of Fig. 2. Fig. 2 is a vertical sectional elevation on the line A A of Fig. 1. Figs. 3 and 4 are sections through the coupling-boxes 10 and 11 on an enlarged scale, Fig. 3 being 25 taken on the line D D of Fig. 4, and Fig. 4 on the line C C of Fig. 3.

Similar reference-numerals refer to similar parts in all views.

The driving device consists of a hollow 30 pillar 1, the interior of which is accessible through doors 2. Inside the pillar is a motor 3, a counter-shaft 4, the pulleys 5, 6, and 7 on the motor and counter-shaft, as well as the belts 8 and 9. Further, there are on the 35 pillar the coupling-boxes 10 and 11, of which 10 is driven directly and 11 through the counter-shaft from the motor. Further, there are base-plates 12 13 on the pillar, on which plates the separate household-machines are fastened, the slow-running machines on plate 12 and the fast-running machines on plate 13. A meat chopping or mincing machine on plate 12 and a polishing-machine on plate 13 are indicated in 40 dotted lines as examples.

For fastening the separate machines the present driving device has the following fastening device. Below the plates 12 13 45 screw-spindles 14, with hand-wheels 15, are revolvably mounted, on the threads of which spindles a key 24 is pushed forward in rotating said spindle, which key is guided between two noses 16 on the plates and is pressed into a slot in a pin in rotating the spindle, said pin

being on the household-machines, adapted to 55 project through a hole in the base-plates 12 13.

For coupling the separate machines to the coupling-boxes 10 and 11, driven from the motor, said coupling-boxes have the following 60 device: They are formed mold shape, and in their interior is a cast eye 17 with borings of different sizes, as well as a pin 18, movable in the eye. This pin has on its part a collar 19, against which a spring 20 in the 65 larger boring of the eye presses, said spring resting on the other side against a nut 21, screwed into the boring. The pin 18 projects somewhat out of the coupling-box 10 or 11, but can be pushed back into the same 70 when the spring 20 is contracted. Said pin serves for automatically engaging in a corresponding hole of a disk on the axle of the different household-machines in order to effect the coupling of these machines with 75 the coupling-boxes. Further, the coupling-boxes 10 and 11 have a cast ratchet 22, by means of which household-machines with vertical axles, like coffee-mills or the like, can be driven, as Fig. 4 shows in dotted 80 lines.

A folding shelf 23 is attached to the pillar below the base-plate 12, which shelf serves for holding vessels and the like.

I am aware that prior to my invention 85 driving devices have been used in combination with a plurality of household-machines. I therefore do not claim such a device broadly. In such cases, however, each machine has had its own motor or at least an intrinsic part of the driving device has had to be removed in order to couple another household-machine to said driving device. In the present case, however, my invention has for its object one integral driving device for all 90 household-machines, and it is not necessary to remove or exchange any part of the device forming the subject of this invention in order to couple household-machines to the same for the purpose of driving them from 95 the same.

I claim—

1. A driving device for household-machines comprising in combination a hollow pillar, a motor in said pillar, a plurality of driving 105 coupling-boxes adapted to be driven by said motor, a plurality of base-plates mounted on said pillar, means for fastening household-

machines to said base-plates, so that said machines are in position to be driven by said coupling-boxes.

2. A driving device for household-machines comprising in combination a hollow pillar, a motor in said pillar, a driving coupling-box adapted to be driven by said motor, a driving coupling-box adapted to be directly driven by said motor, a plurality of base-plates mounted on said pillar, means for fastening household-machines to said base-plates, so that said machines are in position to be driven by said coupling-boxes.

3. A driving device for household-machines comprising in combination a hollow pillar, a motor in said pillar, a driving coupling-box, a counter-shaft, a plurality of pulleys on said counter-shaft in said pillar, means for driving said counter-shaft from said motor, means for driving said coupling-box from one of said pulleys, a driving coupling-box adapted to be driven by said motor, a plurality of base-plates mounted on said pillar, means for fastening household-machines to said base-plates, so that said machines are in position to be driven by said coupling-boxes.

4. A driving device for household-machines comprising in combination a hollow pillar, a motor in said pillar, a plurality of driving coupling-boxes each having a hole, a spring in said hole, a nut adapted to normally engage said spring and to hold same in said hole, a pin engaged by said spring, said pin projecting outside said coupling-box and adapted to automatically engage a revoluble driving part of a household-machine, said coupling-boxes being adapted to be driven by said motor, a plurality of base-plates mounted on said pillar, means for fastening household-machines to said base-plates, so that said machines are in position to be driven by said coupling-boxes.

5. A driving device for household-machines comprising in combination a hollow pillar

having an opening in its side, a door adapted to close said opening, a folding shelf attached to said pillar, a motor in said pillar, a plurality of driving coupling-boxes adapted to be driven by said motor, a plurality of base-plates mounted on said pillar, means for fastening household-machines to said base-plates so that said machines are in position to be driven by said coupling-boxes.

6. A driving device for household-machines comprising in combination a hollow pillar, a motor in said pillar, a base-plate mounted on the top of said pillar, a base-plate mounted on the side of said pillar, a coupling-box mounted revolubly on said top base-plate adapted to be driven by said motor, annular means on said coupling-box adapted to positively engage a revoluble driving member of a household-machine, a driving coupling-box adapted to be directly driven by said motor, means for fastening household-machines to said base-plates so that said machines are in position to be driven by said coupling-boxes.

7. A driving device for household-machines comprising in combination a hollow pillar, a motor in said pillar, a plurality of driving coupling-boxes adapted to be driven by said motor, a plurality of base-plates having slots mounted on said pillar, each base-plate having a screwed spindle revolubly mounted on the same, a key normally engaged by said spindle, guides adapted to said key, said key being adapted to engage means attached to said household-machines whereby the same may be secured in position to be driven by said coupling-boxes.

In testimony whereof I have signed my name to this specification in the presence of the two subscribing witnesses.

RICHARD BRAMBACH.
